CLAIM

The ornamental design for a terminal block of a battery pack, as shown and described.

DESCRIPTION

FIG. 1 is a front perspective view of a terminal block of a battery pack, showing our new design.

FIG. 2 is a rear perspective view of the terminal block of the battery pack shown in FIG. 1.

FIG. 3 is another rear perspective view of the terminal block of the battery pack shown in FIG. 1.

FIG. 4 is a rear view of the terminal block of the battery pack shown in FIG. 1.

FIG. 5 is a top view of the terminal block of the battery pack shown in FIG. 1.

FIG. 6 is a perspective view of a cross-section, taken along lines 6-6 in FIG. 5, of a first side of the terminal block of the battery pack shown in FIG. 1; and,

FIG. 7 is a cross-section view, taken along the lines 6-6 in FIG. 5, of the first side of the terminal block of the battery pack shown in FIG. 1, the cross-section view of a second side of the terminal block of the battery pack being a mirror image of the cross-section view of the first side.

In the drawings, the evenly-spaced broken lines illustrate portions of the article and form no part of the claimed design. The dot-dash broken lines illustrate a boundary to the claims and form no part thereof.
